UNITED STATES PATENT OFFICE.

RUDOLPH C. HAASE, OF MILWAUKEE, WISCONSIN.

TYPE-WRITER CABINET.

SPECIFICATION forming part of Letters Patent No. 590,261, dated September 21, 1897.

Application filed April 12, 1897. Serial No. 631,819. (No model.)

To all whom it may concern:

Be it known that I, RUDOLPH C. HAASE, of Milwaukee, in the county of Milwaukee and State of Wisconsin, have invented a new and useful Improvement in Type-Writer Cabinets, of which the following is a description, reference being had to the accompanying drawings, which are a part of this specification.

10 My invention has relation to improvements in type-writer cabinets of that class in which the type-writer while in use is suitably and conveniently supported in position to be operated upon and while not in use is held and 15 suitably supported within the cabinet.

The object of the present invention is to improve the general construction of such class of devices, so as to obtain the maximum simplicity in construction and ease in operation.

20 With the above primary object and others in view the invention consists of the devices and parts or their equivalents, as hereinafter more fully set forth.

In the accompanying drawings, Figure 1 is 25 a vertical sectional view of my improved type-writer cabinet with the parts as they appear when the cabinet is closed—that is, when the type-writer is supported within said cabinet. Fig. 2 is a similar sectional view 30 showing the parts adjusted to support the type-writer in position to be operated. Fig. 3 is a front view with the parts adjusted as in Fig. 1, and Fig. 4 is a fragmentary under side view of the forward end of the movable 35 cover.

Referring to the drawings, the numeral 5 indicates a type-writer cabinet provided with a large recess 6, open at the front of the cabinet and extending back to the rear wall there- 40 of. The top of the recess is also open, except at the rear or back, where it is covered by a top strip 7, which extends forward for a short distance and terminates in a raised projection 8, and just back of this projection, on 45 the under side of the strip, is formed a bevelled surface 9.

Extending forwardly from the rear wall of the cabinet and near the lower edge thereof and into the recess 6 for a desired distance 50 is a horizontal platform 10. The opposite side pieces of the recess of the cabinet have

secured thereto near their upper edges cleats 11 11.

The numeral 12 indicates the movable sup- 55 porting-table for the type-writer, which is provided at its rear edge with the upstanding flange or strip 13. Pivotedly connected at their upper ends to the opposite side edges of this table, near the front edge thereof, are links 14 14. The lower ends of these links are piv- 60 otally secured to the opposite side pieces of the recess 6. Also connected at their forward ends to medial points of the opposite side edges of the table are other and longer links 15 15. The rear ends of these links are 65 connected to the opposite side pieces of the recess of the cabinet toward the rear of said side pieces. Secured to and depending from the opposite edges of the table, near the rear end of said table, are plates 16 16, said plates hav- 70 ing segmental recesses 17 17 formed therein.

The numeral 18 indicates a movable cover which near its front end is provided with a depending transverse strip 19, which strip is adapted to rest on the forward edge of the 75 table 12 when the cover is at a horizontal position and the table at an inclined position. This forward edge of the table is advisably beveled, as clearly shown in the drawings, so that the lower edge of the depending strip 19 80 will rest squarely thereon. The rear end of this cover when in said horizontal position is adapted to rest against the under side of the raised projection 8, and the rear edge of the table is beveled or rounded, as indicated 85 at 20, so as to clear the bevelled surface 9 of the top strip 7, whereby the adaptability of the cover assuming a true horizontal position is not interfered with.

The numerals 21 21 indicate levers which 90 are pivoted at medial points to the opposite side pieces of the recess 6. Their rear ends are pivotedly connected to the opposite side edges of the cover at the rear thereof. The forward ends of these medially-pivoted levers 95 are provided with inwardly-projecting pins 22 22, which pass into the segmental slots of the plates 16.

The numerals 23 23 indicate links which are pivotedly connected to the side cleats 11 100 and also pivotedly connected at opposite points of the front edge of the cover. The

front transverse strip 19 of this cover is ad-
visably provided at opposite ends with angular recesses 24 24, in which are disposed ears 25 25, to which ears the ends of the links 23 5 are pivoted. These angular recesses provide for setting in the ends of the links 23, so as not to interfere with the closing of the cover in a horizontal position.

Fig. 1 shows the position of the parts when 10 the cabinet is closed or when the cover is ad-
justed to a horizontal position. The type-
writer, as is well understood, is, when the
parts are so adjusted, supported upon the
table and is entirely within and inclosed in
15 the recess 6 of the cabinet. Now if it is de-
sired to open the cabinet and raise the mov-
able table and the type-writer supported
thereby to a position to operate the type-
writer the cover is grasped at its forward
20 edge and swung rearwardly. It swings on
the links 23 23 and at the same time turns
the levers 21 on their pivots, the pins 22 of
said levers riding in the segmental slots of
the plates and traveling from the rear ends
25 of said slots toward and to the forward ends
thereof. The moment they reach the limit
of their forward movement they will act
against the ends of the slots and cause an up
movement of the rear end of the table, said
30 table moving in an arc of a circle with the
pivotal points as centers. When the table
reaches almost a horizontal position, the me-
di ally-pivoted levers 21 have been turned to
such an extent as to cause the inwardly-ex-
35 tending pins 22 thereof to begin a return
travel toward the rear ends of the segmental
slots of the plates. When the table has
finally reached its horizontal position, it will
be seen that its opposite edges will lie be-
40 neath the side cleats 11 11 and that the end
flange or strip 13 thereof will rest against the
inner side of the front strip 19 of the cover.
The front of the table is firmly held against
dropping down by the links 14 14, which have
45 been turned sufficiently after the table has
been brought to a horizontal position to be in
a vertical line with their pivots. When the
table is thus brought to a horizontal position,
the cover of course is necessarily swung to
50 the position shown in Fig. 2, it being sup-
ported in said position by reason of the en-
gagement of its strip 19 with the end flange
13. The upwardly-extending front piece of
the platform 10 serves to entirely cover the
55 space which would otherwise be left between
the inner edge of the table and the rear wall
of the cabinet when the table is swung in-
wardly.

When it is desired to close the cabinet or
60 adjust the parts from the position shown in
Fig. 2 to the position shown in Fig. 1, all that
is necessary is to grasp the front edge of the
cover and swing said cover forwardly. The
cover then turns on the links 23 23, and by
65 reason of the uplifting of its rear edge the
medi ally-pivoted levers are turned upon their

pivots and the inwardly-extending pins 22 of
said levers are caused to travel from the rear
ends of the segmental slots toward the front
ends thereof, and thereby cause a down 70
movement of the table, turning said table to
the inclined position shown in Fig. 1 and the
cover to a horizontal position, said cover hav-
ing its side edges resting on the cleats 11, its
front strip 19 on the forward edge of the ta- 75
ble, and its rear edge being beneath the raised
projection 8.

It will be observed that the medi ally-piv-
oted levers are curved somewhat at their rear
ends. This formation of the levers has the ef- 80
fect of bringing the table and cover to their
different relative adjusted positions at ap-
proximately the same time.

From the above description it will be seen
that my invention is of an exceedingly simple 85
character and is capable of being operated
with the slightest trouble. It dispenses with
all complicated mechanism and renders en-
tirely unnecessary the use of weights, which
are now commonly employed in type-writer 90
cabinets of this class.

A further important feature of my inven-
tion resides in the fact that the table is se-
curely locked in its horizontal position. It
will be seen that when said table is in the po- 95
sition referred to the pins 22 are on a line or
approximately a line with the pivots of the
medi ally-pivoted levers 21, and consequently
pressure applied to the rear end of the table
can have no effect in swinging said table, but it 100
will remain in a locked horizontal position un-
til released by swinging forwardly the cover.
It will also be noted that the cover is locked
in a horizontal position. By reference to Fig.
1 it will be noticed that the pins 22 when said 105
cover is in the horizontal position are at the
ends of the slots 17, and consequently it would
be impossible for the cover to swing inwardly
by pressure applied at its rear, as the circle
described by the pins with the pivots of the 110
medi ally-pivoted levers as centers is less than
the arc of the circles described by the slots
17. It is further locked by reason of the for-
ward end of the table bearing against depend-
ing flange 19 of the covers. 115

What I claim as my invention is—

1. The combination, of a cabinet provided
with a recess therein, a swinging table, a plate
secured to the edge of the table and having
a curved slot therein, a swinging cover, and 120
a medi ally-pivoted lever connected at one end
to the cover, and having its opposite end pro-
vided with a pin or projection extending into
the curved slot of the plate.

2. The combination of a cabinet provided 125
with a recess therein, a swinging table, a plate
secured to the edge of the table and having
a curved slot therein, a swinging cover, and
a medi ally-pivoted lever connected at one end 130
to the cover and having its opposite end pro-
vided with a pin or projection extending into
the curved slot of the plate, the pivot of the

lever being so disposed that when the table is swung to a horizontal position, and the pin of the lever thereby brought to one end of the slot, said pin will be in a line, or approximately a line, with the pivot, whereby the table is locked in its horizontal position against being swung down by pressure applied at the rear.

3. The combination, of a cabinet provided with a recess therein, a swinging table, a plate secured to the edge of the table and having a curved slot therein, a swinging cover, and a medially-pivoted lever connected at one end to the cover and having its opposite end provided with a pin or projection extending into

the curved slot of the plate, the circle described by said pin with the pivot of the medially-pivoted lever as a center being less than the arc of a circle described by the curved slot, whereby, when the cover is in a horizontal position, and the pin of the lever at the end of the slot, said cover is locked in its horizontal position against pressure applied to the rear thereof.

In testimony whereof I affix my signature in presence of two witnesses.

RUDOLPH C. HAASE.
